UNITED STATES PATENT OFFICE.

JAMES F. KEY, OF LONG BEACH, CALIFORNIA.

ADDING-MACHINE.

1,198,851.

Specification of Letters Patent. Patented Sept. 19, 1916.

Application filed June 19, 1914. Serial No. 846,088.

To all whom it may concern:

Be it known that I, JAMES F. KEY, a citizen of the United States, and a resident of Long Beach, in the county of Los Angeles 5 and State of California, have made certain new and useful Improvements in Adding-Machines, of which the following is a specification.

My invention relates to improvements in 10 adding machines, and it consists in the combinations, constructions and arrangements herein described and claimed.

An object of my invention is to provide a device which is simple in operation, and 15 which can be manufactured at small cost for permitting operations that are ordinarily accomplished by machines of much greater complexity and which are comparatively expensive.

20 A further object of my invention is to provide a device of the type described comprising a rotatable number disk which actuates an indicating wheel with means for holding the number disk and the wheel in 25 their various positions and for instantly releasing the wheel to permit its return to its initial position.

Other objects and advantages will appear 30 in the following specification and the novel features of the device will be particularly pointed out in the appended claims.

My invention is illustrated in the accompanying drawings forming part of this application in which—

35 Figure 1 is a plan view of the device, Fig. 2 is a view of the under side of the operative mechanism, Fig. 3 is a section along the line 3—3 of Fig. 2, Fig. 4 is a section along the line 4—4 of Fig. 3, Fig. 5 is a face view of 40 the number disk, Fig. 6 is an enlarged plan view of a portion of the device showing the apparatus in one position, Fig. 7 is a view similar to Fig. 6 showing the apparatus in another position, Fig. 8 is a section along 45 the line 8—8 of Fig. 1 looking in the direction of the arrows, Fig. 9 is a section along the line 9—9 of Fig. 8, Fig. 10 is an enlarged section along the line 10—10 of Fig. 3, Fig. 11 is a plan view of a modified form of the 50 device, and Fig. 12 is a section along the line 12—12 of Fig. 11.

In carrying out my invention I provide a casing preferably of metal and of substantially triangular cross section, as shown in Fig. 8. In this figure it will be seen that

there is an inclined front plate 1 having an integral back portion 2, these parts being secured to a bottom member 3. The latter is provided with a peripheral flange 3^x which forms a stiffening member and also convenient means for attachment. The ends of the casing consist of castings such as that shown at 5 in Fig. 9, these castings being provided with recesses 5^x for the nuts 6 of longitudinal brace bars 7.

60 Referring now particularly to Fig. 1 it will be seen that the plate 1 may be provided with one or more circular openings 8 bordered by a series of radially extending lines 9, which divides the edge of the wheels adjacent to the opening into 100 parts, these parts being designated by numerals 10, which range from zero to 99 inclusive. Although in Fig. 1 I have shown two openings, it will be understood that this is merely 65 for the sake of convenience in having two separate adding machines on one plate, each of these machines being otherwise entirely separate and distinct from each other. A description of one therefore will suffice for 70 both.

75 Referring now particularly to Fig. 5, it will be seen that I have provided a disk 11 of substantially circular shape, the edge of the disk, however, being formed in the 80 manner of a spiral such as an involute and being provided with a downwardly turned flange 11^a shown in dotted lines in Fig. 1 and in full lines in Figs. 3 and 8. The disk 11 is provided with an inner circular row of 85 openings 11^b and with a concentric row of similar openings 11^c which are staggered with respect to the openings 11^b in order to permit a greater number of openings of a given size than if these openings were disposed at the same distance from the center of the disk. Each of these openings has an 90 indicating line 11^d which extends radially. The openings are numbered from zero to 95 99 by a concentric row of numerals 11^e. An outer concentric row of openings 11^f is provided for a purpose hereinafter described. As will be seen from Fig. 3, these openings 100 11^f are in a portion of the disk which is raised from that portion bearing the numerals.

105 In Figs. 2 and 3 I have shown a plate 12 which is spaced apart from the face plate by means of blocks or posts 13, the latter being held in position by means of screws 110

14 or in any other suitable manner. Carried by the plate 12 is a cylindrical housing 15, whose upper portion is flanged at 15^a so that the housing may be riveted to the plate. 5 This housing forms part of a bearing for a central pivot post 16, which is provided with a sleeve 17, the latter forming a retainer for anti-friction balls 18. The top part of the post is provided with a head 16^a which is flanged so as to receive and retain the disk 11 and a washer or strengthening disk 19. After these parts are placed in position they are riveted as shown in the drawings. The lower portion of the pivot post 16 is recessed to receive a spring 20, while a ball 21 is disposed at the bottom of the recess, the spring 20 resting upon the ball. A central passage way 22 extends from the top of the pivot post to the recess in which 15 the spring 20 is disposed. At the bottom of the pivot post 16 are lateral projections 16^b which serve to support the ball retainer 17.

As will be seen from Figs. 2, 3 and 8 the U-shaped bracket 23 is secured to the plate 12. This is provided with a transverse pivot bar 24 upon which is pivoted a U-shaped frame member 25 extending normally at right angles to the U-shaped bracket 23, as shown in Fig. 3. Pivoted between the arms 30 of the U-shaped frame member 25 is the shaft 26 of a wheel 27 having teeth 27^a. The shaft 26 bears a spiral spring 28, one end of which is connected with the wheel 27, the other end being connected with a portion of the frame 25. The frame 25 bearing the wheel 27 is held in an upper position by means of a spring 29 secured to the plate 12 (see Fig. 3). A push rod 31 is pivotally connected at 32 to the frame 25 and extends outwardly through an opening in the face plate 1, being bent laterally to provide a thumb portion, as shown in the drawings.

As will be plainly seen from Fig. 3 the 45 teeth 27^a of the wheel 27 are designed to be engaged by the downwardly depending flanges 11^a of the disk 11, and it is obvious that as the disk 11 is turned the wheel 27 will be rotated.

50 The plate 1 is provided with an opening 33 through which numbers 34 on the outer faces of the teeth may be observed. This opening 33 is connected with a slot 35 through which the numbers 11^c of the disk 55 11 may be observed as they come into registration with the slot. A projection 11^k extends inwardly over the disk 11, as shown in Fig. 1, this projection extending past the concentric rows of openings 11^b and 11^c 60 of the disk.

At 36 in Fig. 1 I have shown an indicating hand arranged to play over a dial 37. This hand may be connected with the number wheel 27 in order to indicate the number 65 of revolutions of the wheel.

From the foregoing description of the various parts of the device the operation thereof may be readily understood.

In setting the number wheel to zero, it is only necessary to depress the push rod 31. 70 This will free the teeth 27^a from the flange 11^a whereupon the spring 28 will rotate the wheel until a stop pin 38 on the wheel 27 engages a stop member 39 carried by the bracket 12. If now the point of a pencil 75 or other pointed implement be inserted in the opening 40 in the face of the disk 11 and the latter is rotated in a direction opposite to that of the arrow shown in Fig. 1, the apparatus will have assumed the position shown in Fig. 6 in which the number zero on the wheel 27 appears in the opening immediately adjacent to the edge of the disk 11, while the number double zero appears in the slot 35. In adding a column 80 of figures, as for instance 7, 23, 89, 46, 92, 61 and 33, the point of the pencil or implement is inserted in the opening opposite the numeral 7, a slight pressure is applied downwardly while the disk is rotated in 90 a clockwise direction shown by the arrow until the implement comes into engagement with the stop member 11^k. The numeral 7 will now appear in the slot 35. In pressing down on the disk 11 the latter is moved 95 slightly downwardly against the tension of the spring 20 (see Fig. 3) to free it from frictional engagement with the under side of the plate. When the pencil is removed the plate springs back into position so as to 100 hold the disk stationary by frictional engagement. In order that the disk may be turned precisely to the proper position I provide a rigid centering member 41 (see Fig. 4) which is tapered to enter the openings 11ⁱ so as to bring the disk in the proper position. Furthermore this member tends to aid in retaining the disk in position. When 105 the disk 11 is moved downwardly as described, it is free from the centering member 41. The pencil is now put in the opening corresponding to the numeral 23 and the operation is repeated and so on with the remaining numbers. The rotation of the disk will cause the rotation of the number wheel 27 through the engagement of the flange 11^a with the teeth of the number wheel. Since the number wheel is only rotated one tooth for every revolution of the disk it will be apparent that the figures 115 on the number wheel represent hundreds so that in the example just given when the machine has been operated the figure 3 will appear in the opening 33, while the numeral 51 will appear in the slot 35, thus showing 120 125 at a glance that the sum of the numerals is 351.

Of course, a wheel 27 of sufficient size might be employed to have any given number of teeth, but in practice I prefer to em- 130

ploy a wheel having forty teeth. One of these is larger than the others. This tooth is shown at 42 in Fig. 3. It is obvious that when this tooth is reached there can be no further rotation in a clockwise direction of the wheel 27. The purpose of the indicating dial 37 is to register the number of revolutions of the wheel 27 so that when the wheel 27 has turned one revolution the pointer 36 on the indicating dial may be set at 1. On pressing the push rod 31 the wheel 27 will move downwardly out of engagement with the flange 11^a and the spring 28 will return it to zero in the manner stated. It is possible with a device of this kind when one becomes expert to add a column of figures very rapidly and since the action of the revolving disk upon the number wheel is positive the machine is absolutely accurate.

As will be seen from Figs. 6 and 7 the edge of the disk 11 takes the place of a pointer and the eye can instantly see the proper number on the wheel because it is immediately adjacent to the edge of the disk. This does away with the necessity of a pointer and permits the operation of the device in a much more rapid manner than with other devices in which the mechanism is more complicated.

In Figs. 11 and 12 I have shown a modified form of the device in which the plate 1' is provided with a bearing 15' similar to the bearing 15 in which a disk 11' similar to the disk 11 is mounted. A plate 12' has a bracket 43 which carries a bearing 44 for the shaft 45 of a wheel 46. The opposite end of the shaft is journaled in a bearing 47 in the plate 1. The wheel 46 is provided with teeth 46^a which extend laterally from the plane of the wheel and which are designed to be engaged by the downwardly extending flange 11^x of the disk 11'. The plate 12 bears a stop member 48 arranged to engage a stop member 49 on the wheel 46. The wheel 46 bears a wide tooth 50 against which the end of the shoulder 11^y of the disk 11 engages when the wheel 46 is being rotated one turn.

The operation of this form of the device is similar to that already described. In both cases the number of the tooth on the number wheel nearest the edge of the rotatable disk indicates hundreds, while the tens and units are indicated by the figures on the face of the disk itself. In Fig. 11 it reads 299, the 2 appearing on the number wheel 46 and 99 appearing in the slot 35'.

I claim:

1. In an adding machine, a rotatable disk having a laterally extending spiral flange, a rotatable number wheel having a series of teeth arranged to be engaged successively by the flange, the rotation of the disk one turn serving to rotate the number wheel a distance corresponding to one tooth, said

number wheel being provided with an enlarged tooth, whereby rotation of the disk is stopped when the flange engages said tooth.

2. In an adding machine, a rotatable disk, 70 a rotatable number wheel disposed adjacent to said disk and having a portion adapted to be covered by the disk, a laterally extending flange carried by the disk, a series of numbered teeth carried by the number wheel 75 and arranged to be engaged successively by the flange on the rotation of the disk, one turn of the disk serving to rotate the number wheel the distance of one tooth and to thereby cover or uncover one of the numbers carried by the number wheel, and means for holding the disk frictionally in any of its positions, said last-named means comprising a spring on the side of the disk facing the number wheel, and an abutment 80 member on the opposite side of the disk.

3. The combination with a rotatable disk having a laterally extending flange formed in the manner of a worm, a number wheel having its axis at right angles to the axis 90 of the disk, said number wheel being provided with teeth having numbers on their outer faces, said teeth being arranged to be engaged by the laterally extending flange and to be moved the space of one tooth for 95 each revolution of the disk, said disk being movable bodily along its axis of rotation, a spring for normally forcing the body portion of the disk away from the wheel, and means on the opposite side of the disk for 100 frictionally engaging the body portion of the disk.

4. The combination with a rotatable disk having a laterally extending flange formed in the manner of a worm, a number wheel having its axis at right angles to the axis of the disk, said number wheel being provided with teeth having numbers on their outer faces, said teeth being arranged to be engaged by the laterally extending flange and to be moved the space of one tooth for each revolution of the disk, said disk being movable bodily along its axis of rotation, a spring for normally forcing the body portion of the disk away from the wheel, and a 115 casing member on the opposite side of the disk from the wheel adapted to engage and frictionally hold the disk in any of its positions.

5. The combination with a rotatable disk 120 having a laterally extending flange formed in the manner of a worm, a number wheel having its axis at right angles to the axis of the disk, said number wheel being provided with teeth having numbers on their outer faces, said teeth being arranged to be engaged by the laterally extending flange and to be moved the space of one tooth for each revolution of the disk, said disk being movable bodily along its axis of rotation, a 125 130

spring for normally forcing the body portion of the disk away from the wheel, a casing member on the opposite side of the disk from the wheel adapted to engage and 5 frictionally hold the disk in any of its positions, said casing having an opening for ex-

posing to view the tooth of the wheel which is in engagement with the flange of the disk.

JAMES F. KEY.
